FLUID CONDITIONER PIPELINE UNIT

Arthur N. Wells, Belmont, Calif.

Application July 16, 1954, Serial No. 31,477

Term of patent 14 years

(Cl. D91—3)

FIG. 1.

FIG. 2.

Fig. 1 is a perspective view showing one side of a fluid conditioner pipeline unit embodying my new design; and Fig. 2 is an end view of the unit.

I claim:

The ornamental design for a fluid conditioner pipeline unit, as shown.
